JERSEY

POSITION INDICATOR FOR ELEVATORS

Application filed April 6, 1926. Serial No. 100,009.

This invention relates to improvements in elevator signalling devices and is particularly designed to indicate both the position and direction of movement of a movable elevator.

It is a particular object of the invention to provide a mechanism for indicating the position and direction of movement of an elevator by means of a column of light so that the position and direction of movement of the elevator can be obtained at a glance from the signalling portion of the apparatus.

It is one of the primary objects of the invention to provide an apparatus of this character in which all of the parts may be positively actuated to limit the possibility of the same becoming out of order.

It is a further object to provide suitable adjustments for the various operating parts of the mechanism so that uniformly built sets of the mechanism may be adjusted to the various conditions of any usual building in which the same are to be installed.

These and other objects will appear more fully from the following description when considered in connection with the drawings in which:

Fig. 1 is an elevational view of a bank of elevators showing our invention applied thereto, certain parts being in section and other parts being broken away, and certain other parts being diagrammatically illustrated.

Fig. 2 is a sectional view of the visual signalling device and the circuit controller constructed according to our invention.

Fig. 3 is a plan view of the visual signalling device with parts broken away to show the interior construction thereof.

Fig. 4 is an elevational view, parts being in section, of the elevator operated controlling mechanism for the signalling apparatus.

Fig. 5 is an elevational view of a portion of the control apparatus shown in Fig. 4 showing the relation thereof to the circuit controller of Fig. 6.

Fig. 6 is an enlarged elevational view of the circuit controller employed herein.

Fig. 7 is a sectional view on the line 7—7 of Fig. 2.

Fig. 8 is a similar section on the line 8—8 of Fig. 2.

Fig. 9 is a perspective view of a conductor 55 shown in Fig. 4.

Fig. 10 is a sectional view taken on the line 10—10 of Fig. 5, and

Fig. 11 is an end view of the clutch mechanism shown in Fig. 10 with certain parts 60 broken away.

We have shown our invention as applied to a bank of four elevators in a building having eight floors to be indicated. While certain details of the elevator construction such as the supporting mechanism therefor is disclosed, it is to be understood that these are merely illustrative and are not a part of our invention.

Referring to the details of the drawings, 70 there is shown in Fig. 1 a plurality of elevator shafts 12a, 12b, 12c and 12d for the movable elevator cars, one of which is indicated at 14. Each of the elevators is controlled by suitable mechanism shown as typical cables 15 and pulleys 16 supported upon rotatable shafts 18. The signalling apparatus in the present embodiment of the invention is operated by the rotation of the shaft 18 which operates through the controlling mechanism indicated generally by the numeral 20 for moving the circuit controlling mechanism indicated generally at 22, resulting in suitable indications at the visual signalling device 24 for indicating the position and direction of movement of the elevator

75 as hereinafter fully described. It is to be understood that each elevator is provided with a complete signalling apparatus comprising in the present embodiment the elevator control shaft 18, signal operating mechanism 20, circuit controller 22 and one section of the visual indicating device 24.

80 The controlling or transmitting mechanism 20 for the signalling apparatus is constructed as follows. A suitable base 26 supports an upstanding bracket 27 and bearing brackets 28 and 29. The rotatable elevator shaft 18 carries a bevel gear 30 which meshes with a bevel gear 31 carried by the vertical shaft

85 90 95

32, which in turn is geared to rotate the transverse shaft 34 supported in the bearings 28 and 29, the gears connecting the shafts 32 and 34 being shown as covered by the gear housings 35. The gears 30 and 31 are preferably of the same size as are also the gears connecting the shafts 32 and 34 so that the latter shaft will rotate at the same rate as the elevator shaft 18.

10 The shaft 34 terminates in a cross head 36 which carries a plurality of projecting clutch pins 37 (Fig. 10) positioned within openings 38 within the clutch head 40. The head 40 is provided with a series of radial openings 15 42 (Fig. 11) in each of which there is mounted a slideable clutch member 43 pressed inwardly of the head by means of a coil spring 44 held in place by the adjustable nut 45. Since the several clutch members and spring are 20 similarly constructed only one is shown in detail in Fig. 11.

The inner ends of the clutch members are constructed to engage the outer surface of a hub member 46 positioned within the head 40 25 and secured to or formed integrally with the gear 48. The gear 48 is supported by the bearing pin 49 and meshes with an intermediate gear 50 supported upon the bearing pin 51 carried by the bracket 27, the gear 50 in turn meshing with an enlarged reduction gear 52 secured rigidly to a relatively small pinion 54 and supported by a suitable bearing pin 53 carried by the bracket 27. The pinion 54 meshes with the teeth 55 formed 35 upon the supporting member or drum head 56 which supports the flexible operating member 63. The drum 56 is preferably adjustably supported with relation to the bracket 27 as by means of the vertically adjustable bearing pin 57 the reduced shank portion 40 58 of which is adjustably supported within the slot 59 formed in the bracket 27 and suitably secured therein, as shown for example in Fig. 4. The adjustment provided by the slot 59 permits the use of various sizes of drums 56 or pinions 54 so that by an exchange of these parts an adjustment for a small or larger building may be readily accomplished.

50 The controlling element or chain 63 for the elevator signalling apparatus is designed to be supported upon the drum or head 56 and to this end a plurality of radially adjustable projections or pins 60 (Fig. 4) are adjustably secured within the slots 61 formed therein. It will thus be seen that the effective circumference of the drum formed by the pins 60 is adjustable within the length of the slots 61 to increase or decrease the movements of the operating member 63 with respect to the angular movement of the drum 56 and shaft 18. Cylindrical spacers 62 are preferably provided upon the pins 60 for receiving the member 63.

55 It is considered desirable to limit the

angular movement of the supporting head 56 to its normal angular movements so that if for any reason, such as slippage between the cables 15 and drums 16, the relation between the drum head 56 and position of the corresponding elevator should become out of adjustment the correct relationship between these parts will be automatically reestablished. To this end the stop members 64 and 65 are secured to the head 56 in position to 70 be moved into engagement with the pinion 54 when the extreme low and high positions respectively of the elevator have been reached. If desired the stop members 64 and 65 may be adjustably secured to the head 56 or 75 to another of the movable elements of the mechanism for supporting the control member 63, for example the gear 52, so as to be accurately positioned with relation to suitable stop devices. It will be understood that 80 if the movable controlling element 63 and head 56 should become out of adjustment with relation to the elevator 14, one of the stops 64 or 65 would engage the pinion 54 and retain the head 56 and element 63 in its extreme normal position while the elevator completed its movement in this direction, the clutch 36—46 accomodating relative movement between the operating shaft 34 and the operated gear 48.

95 For the purpose of reversing the electric control circuits hereinafter referred to, the reversing switch comprising the movable arm 66 and fixed bracket 68 are provided adjacent the transverse shaft 34 and supported 100 on the base 26. The bracket 68 is formed of an insulating material such as bakelite or hard rubber and supports a plurality of separated conducting sections 70, 71 and 72, the sections 71 and 72 being spaced by means of 105 the insulator 73 having a surface flush therewith, as shown particularly in Fig. 5. The length of the sections 71 and 72 is such that a small reverse movement of the elevator will not reverse the indicating mechanism but, on the contrary, a reversal of several feet in the elevator will be required before the indicator is changed, as will hereinafter more fully appear. Electric current is supplied to the terminal 74 of the conductor 70 by means of a 110 conductor 75 connected with a suitable source of current supply. The terminals 76 and 77 of the conductors 71 and 72 connect with suitable conductors 124 and 125 respectively, designed to lead the current supplied thereto to the electric controlling mechanism 22, as described below. The arm 66 is also preferably formed of an insulating material and is mounted upon the shaft 34 for rotation with or with respect to the said shaft. To this end the arm 66 has a separate section 78 slidably positioned upon pins 79 and pressed into engagement with the shaft 34 by means of the springs 80 mounted on the pins 79 between the heads of the pins and the section 78. The 115 120 125 130

longitudinal position of the arm 66 upon the shaft 34 may be maintained by means of the fixed collar 82.

The purpose of the arm 66 and bracket 68 is to reverse the flow of current to the controlling apparatus 22 upon a reversal of the direction of movement of the elevator. The arm is accordingly supplied with an electrical conductor comprising the yoke 85 (Figs. 4 and 9) the terminals 88 of which engage the slidable pins or brushes 90 and 91. The yoke 85 is formed with a slot or opening 86 which may be slidably passed over the pin 84 carried by the arm 66. A suitable spring 87 holds the conducting yoke 85 in engagement with the brushes 90 and 91 and the latter in engagement with the conductors 70 and 71 or 72. The spring 87 further serves to hold the arm 66 in engagement with the collar 82. The clutch formed by the separate section 78 causes the arm 66 to be rotated with the shaft 34. For the purpose of limiting the rotative movement of this arm a rigid pin 92 projects from one face thereof a distance sufficient to permit it to be engaged with the upper surface of the bracket 68, with the result that the arm 66 is limited to a rotative movement of substantially 90°. It will thus be seen that rotation of the shaft 34 in either direction causes the reversing switch to bridge the conductors 70 and 71 or 72 for supplying current to one of the leads from the terminal 76 or 77 for the purpose referred to below.

The controlling mechanism for the signalling devices operated from the movable member 63 is indicated generally by the numeral 22 and may be positioned at any desired location along the elevator shaft. We have shown the same as positioned adjacent the first floor so that relatively short conductors will be required to couple the same with the signalling devices. The controlling mechanism 22 includes an inner housing 94 for slidably receiving the circuit controller 96 connected by means of the cable 97 with the flexible member 63. Adjustment of the length of the cable 97 may be provided by means of the turnbuckle 97' or other equivalent means. The housing 94 is formed of an insulating material such as bakelite and is provided with open ends permitting the passage of the controller 96 through the same. The housing includes the front wall 98 and rear wall 99 connected by side walls 100. The front wall 98 is apertured to receive a plurality of slidable contact members or brushes 110 and 111 formed in two series as indicated for example in Figs. 2 and 7. The brushes 110 and 111 are pressed inwardly into engagement with the circuit controller 96 by means of the yokes 102 which may be formed as shown in Fig. 9. The yokes 102 are slidably arranged upon the pins 104 carried by the face plate 98 of the housing 22. Springs 105 are positioned upon the rods 104 and bear against suitable collars

thereon and against the yokes to create an inward pressure upon brushes 110 and 111. The brushes 110 and 111 are connected in conducting relation by means of the yokes 102, each corresponding pair of brushes being coupled to separate binding posts 113 as by means of the conductors 109. Conductors 112 secured to the binding posts 113 and to binding posts 114 supply the electric current from either of the brushes 110 or 111 of each set to one of the signalling units as will appear more fully below.

Current is supplied to the circuit controlling mechanism 22 by means of the conductors 124 and 125 leading respectively from the conductors 71 and 72 to the binding posts 126, 126a and 127, 127a, respectively, from which conductors 116 lead to the four power terminals or brushes 122, 122a, 123 and 123a respectively. Each pair of terminals 122 and 123 and 122a and 123a may be supported as shown in Fig. 8 wherein the yoke member 118 formed of insulating material is slidably mounted upon the pin 104 and normally pressed inwardly by means of the compression springs 105. The yoke 118 carries pins 120 engaging with slidable brushes or contact members 122 and 123 for pressing the same inwardly into engagement with the controller 96. The mechanism shown in Fig. 8 for controlling the power terminals 122, 122a, 123 and 123a is substantially the same as that shown in Fig. 7 for the brushes 110 and 111 the main difference being that the yoke 118 (Fig. 8) is formed of insulating material whereas the yoke 102 (Fig. 7) is formed of conducting material. According to the above described construction either the conducting line 124 and conductor 70 are placed in conducting relation with the brushes 122 and 122a or the conducting line 125 and conductor 70 are placed in conducting relation with the brushes 123 and 123a. The power line 75 is accordingly connected to either the terminals 122 and 122a or 123 and 123a dependent on the position of the reversing switch lever 66.

The circuit controller 96 is formed as a bar of insulating material upon one surface of which there are positioned a number of conducting and insulating elements as shown particularly in Figs. 5 and 6 placed in two series indicated generally by the numerals 128 and 128a. The conducting and insulating surfaces of the series 128 and 128a are identical in construction but are arranged in reverse relation with respect to the length of the controller. Each section comprises an insulating surface 129 (129a), a conducting element 130 (130a), a relatively short insulating surface 131 (131a), an elongated conducting element 132 (132a), and a final insulating surface 133 (133a). The maximum length of the sections 128 and 128a is approximately twice the distance between the terminal contact devices 122, 123, and 122a, 123a.

123a of the circuit controlling apparatus. In order that the controller 96 will be positively moved downwardly through the housing 22, a weight 134 or equivalent device may be attached to an end of the same, as shown in Figs. 2 and 6. The entire circuit controlling mechanism 22, 96 may be enclosed in a suitable casing, as shown for example at 136 in Fig. 2, the outer face of the casing being provided with a hinged closure (Fig. 1).

10 The visual signalling device 24 includes a casing 138 provided with a hinged closure formed with a plurality of vertically arranged sections of frosted glass forming sight elements 140, one such element being provided for each elevator to be indicated in the system. Each of the elements 140 is preferably formed as an unbroken section of semi-transparent glass having indicating portions 140a, 140b etc. for indicating the various positions of the elevator associated therewith. The portions 140a, 140b etc. are defined by means of transverse partitions 141 and vertical partitions 142 carried within the casing 138 and forming pockets 143 in each of which is positioned an electric light 144. The lights 144 are carried by a conducting baseboard 145 supported from the insulating base plate 148 and terminating in the binding post 146. A power circuit 150 extends from the binding post 146 to a suitable source of electric current supply (not shown) to complete the circuit formed with the conductor 75 shown in Fig. 5. The binding posts 152 carry spring contacts 153 positioned adjacent the lights 144 for contact therewith for energizing the same when current is supplied to the terminals 114 thereof, as described above. The casing 138 may be completed by means of the top and side walls 139 and rear walls 141 supported by the angle irons 139a which in turn support the insulating baseboard 143 and other interior mechanism therein. It is preferred that each of the indicating sections 140 be formed as a single piece of frosted glass, as described above, so that the resultant indication will appear as a continuous elongated beam of light on the same for indicating the position and direction of movement of the elevator although obviously, if desired, it may be formed in separate sections. While we have shown only one signalling device 24 it is to be understood that this mechanism may be duplicated, for other positions in which it is desired to indicate the position and direction of movement of the elevator.

15 The operation of the apparatus will now be described. When any elevator is in its lowest operative position the parts of the signal controlling apparatus will assume the position shown in Fig. 5. The drum head 56 will have been rotated clockwise to the limit of its movement and the stop member 64 will be substantially in engagement with the pinion 54. The flexible element 63 will

have been unwound from the pins 60 and the circuit controller will be in its lowermost position. Rotation of the shaft 34 and the switch arm 66 in a counter-clockwise direction will have closed the circuit from the power line to the terminals 123 and 123a. The circuit at 123 will be open since this terminal rests upon the insulating section 138a of the controller. The conducting section 130a bridges the terminal 123a and the contact 110 leading to the lowermost light 144a causing the corresponding portion of the sight element 140 to be illuminated. As the elevator moves upwardly it causes a clockwise rotation of the shaft 34 and a counter-clockwise rotation of the drum head 56 with the result that the switch lever 66 moves into position to bridge the conductors 70 and 71 and the flexible member 63 is moved upwardly carrying with it the circuit controller 96. After this movement has continued to a very slight extent the conducting section 130a of the controller 96 will have moved out of engagement with the brush 123a and at about the same time the switch lever 66 moves from the conductor 72 to the conductor 71 opening the circuit to the conducting line 125 and closing the circuit between the supply line 124 attached to the conductor 71 and the source of electrical supply 75. This results in a supply of electricity being available at the terminals 122 and 122a so that immediately the current is supplied from the power terminal 122a to the contact brush 110 of the lowermost indicating light 144a. The power terminal 122 at this time rests upon the insulating section 129 of the controller 96 and is ineffective to produce light at the visual indicator. As the controller 96 is moved upwardly successive brushes 110 are contacted by the conducting section 132 of the controller so that, by means of the leads 112, successive lights 144 and the corresponding sections of the visual indicator are caused to be illuminated and to remain illuminated until the elevator reaches substantially the end of its path of movement. The visual effect on the indicator produced by this operation is that of an upright column of light which for this, the upward movement of the elevator, has a fixed or stationary base corresponding to the position of the elevator at the beginning of its upward movement while the free end or top of the lengthening column lengthens or projects itself in the direction of the rising elevator giving the effect of a luminous pointer the end of which directs itself in an upward direction as the elevator moves while the position of the end at any time indicates the position of the elevator in the shaft. If at any intermediate position the elevator is reversed a substantial distance the switch 66 is rotated to open the circuit leading to the terminal 122a and segment 132 and closes the circuit to the ter-

10 minal 123 and segment 132a with the result that the upwardly extending column of light is displaced by a downwardly extending or inverted column of light suspended from its fixed base at a point corresponding to the position of the elevator at the uppermost possible end of its upward movement while the free or downwardly pointing end of the column extends or projects itself downwardly with the downward motion of the elevator

15 10 thus giving the same visual effect of a shaft or column of light pointing in the direction in which the downwardly moving elevator is temporarily proceeding. This lengthening inverted column builds up in the downward direction until the elevator is again reversed or reaches the end of its path of movement. When the controller 96 has reached the upper limit of its movement and the stop member 20 65 has reached a point adjacent the pinion 54, the lefthand section 128 of the controller is in the position of the righthand section 128a shown in Fig. 5 so that the uppermost 25 signal light 144b will be energized through the terminal 122 and conducting segment 130 of the controller. As the elevator is reversed and is moved downwardly the operation of the parts is the reverse of that just described, with the result that first the top light of the 30 series is illuminated and thereafter each successive light is illuminated and remains illuminated until the elevator has reached substantially the end of its path of movement whereupon the lights are all extinguished except that which indicates the present position of the elevator, namely the lower landing. As will be seen the visual effect of lighting the lamps seriatim on the downward movement of the elevator and retaining them 35 in circuit is in this instance to produce an inverted column of light lengthening in the direction of movement of the elevator and having the base of the suspended column coinciding with the uppermost position of the 40 elevator. The advancing of the end of the inverted column or lengthening of the same downwardly gives the effect of a pointing column of light extending or pointing in the direction in which the elevator proceeds 45 while the location of the point or end at any time indicates the position of said elevator.

50 In Fig. 1 the various positions of the elevator are indicated as follows. Elevator No. 1 is descending and has almost reached the end of its path of movement so that the column of light is about to be extinguished. Elevator No. 2 is at rest at its highest landing and elevator No. 3 is at rest at the lowest landing. Elevator No. 4 is ascending and 55 60 has reached the position indicated, namely the fourth floor.

By the above described instrumentalities we provide means for indicating at a glance the position and direction of movement of an elevator. While we prefer to employ a

single and continuous column of light for each elevator it will be understood that if desired the indicating portions thereof may be separated units for indicating the different positions of the elevator. Changes may 70 also be made for adapting the apparatus for particular buildings by illuminating the indicating portions of less than the whole number of indicating portions thereof. For example it may be preferred to have only the 75 terminal lights 144a or 144b illuminated when the elevator is in an intermediate position. This can be readily accomplished by placing only the selected contacts 110 and terminals 122, 123, 122a and 123a in position 80 to be engaged by the whole length of the conductors 132 and 132a and permitting the other contacts 110 to be engaged by relatively short side extensions of these conductors. Various other changes may be made in the 85 construction by those skilled in the art without departing from our invention, the limits of which are to be ascertained from the subjoined claims.

90 We claim:

1. In an elevator signalling apparatus, the combination with an elevator, of an electric controller operating synchronously with the elevator and electric lighting devices controlled thereby and operating by the same series of lighting devices to build up a gradually lengthening column of light indicating the position and either direction of movement of the elevator, said column for the upward travel of the elevator lengthening upwardly 100 and having a fixed base maintained in position corresponding to the down position of the elevator and for the down travel being an inverted column which lengthens downwardly while its base is maintained in position corresponding to the up position of the elevator.

105 2. In combination with a vertically movable elevator, a signalling mechanism comprising a plurality of electrically energized elements, means controlled by the position of said elevator for successively energizing said elements, said means causing certain of the energized elements to remain in an energized state after succeeding elements have been energized, and means responsive to the movement of said elevator when the direction of movement of said elevator is reversed for de-energizing said energized elements but retaining a final element in energized condition 110 as the first element for the succession energized in reverse order as the elevator reverses its travel.

115 3. In an elevator signalling apparatus, a plurality of signal lights formed with separate contact points, a circuit controller, means for conducting electric current to a terminal adjacent said circuit controller, said circuit controller including an elongated electrical conductor normally positioned for successive 120 125

- engagement with said contact points and said terminal, said elongated conductor being of a length capable of bridging substantially all of said contact points while in circuit with said terminal and means responsive to the movements of said elevator for moving said controller relatively to said contact points and terminal for lighting and maintaining lighted successive lights corresponding to points reached and passed by said elevator.
- 10 4. In an elevator signalling apparatus, a plurality of signal lights, duplicate sets of contact points for said lights, a circuit controller, means for conducting electric current to a plurality of terminals adjacent said circuit controller, said circuit controller including a plurality of elongated electrical conductors positioned to be engaged by said contact points and by said terminals, said elongated conductors being of a length capable of bridging substantially all of said contact points while in circuit with one of said terminals, said elongated conductors being arranged in opposed relation on said circuit controller to cause one of said conductors to be moved into contact with one of said sets of contact points as the other conductor is removed away from the other of said sets and means responsive to the movements of said elevator for moving said controller relatively to said contact points and terminals for lighting and maintaining lighted successive lights corresponding to points reached and passed by said elevator.
- 15 5. In an elevator signalling apparatus, a plurality of signal lights for indicating the position of said elevator, means for lighting lights corresponding to the various positions of said elevator and for maintaining said lights lighted after said elevator has passed said positions, said means including plural sets of spaced contacts for said lights arranged in separate series, a circuit controller having plural conductors and insulators, said circuit controller being movable relatively to said contacts to cause said conductors and insulators to be moved along and engaged with successive contacts of said sets, means for conducting electricity to a position adjacent said circuit controller, said means terminating in duplicate terminals positioned at spaced points to be engaged by the conductors and insulators of said circuit controller, and means responsive to the position of said elevator for moving said circuit controller.
- 20 6. In an elevator signalling apparatus, a plurality of signal lights for indicating the position of said elevator, means for lighting lights corresponding to the various positions of said elevator and for maintaining said lights lighted after said elevator has passed said position said means including plural sets of spaced contacts for said lights arranged in separate series, a circuit controller having plural sets of spaced conductors, said circuit

controller being movable relatively to said contacts to cause said conductors to be moved simultaneously along and engaged with successive contacts of said sets, means for conducting electricity to a plurality of spaced positions adjacent said circuit controller, said means terminating in plural terminals positioned to be engaged by the conductors of said circuit controller, means responsive to the position of said elevator for moving said circuit controller, and reversible means for closing the electric circuit to one of said terminals and opening the circuit to the other, said last named means being responsive to the direction of movement of said elevator.

25 7. In an elevator signalling apparatus, a plurality of signal lights for indicating the position of said elevator, means for lighting lights corresponding to the various positions of said elevator and for maintaining said lights lighted after said elevator has passed said positions, said means including duplicate sets of spaced contacts for said lights arranged in separate series, a circuit controller having duplicate conductors and insulators, said circuit controller being movable relatively to said contacts to cause said conductors and insulators to be moved simultaneously beneath successive contacts of said sets, means for conducting electricity to a position adjacent said circuit controller, said means terminating in duplicate sets of spaced terminals positioned to be engaged by the conductors and insulators of said circuit controller, said terminals of each set being spaced a distance substantially equivalent to the entire length of said sets of spaced contacts of said lights, and means responsive to the positions of said elevator for moving said circuit controller.

30 8. In an elevator signalling apparatus, a plurality of electrically operated signals, separate contacts for said signals, means for conducting electricity to a point adjacent said contacts, spaced terminals for said conducting means, said contacts and terminals being arranged in substantial alinement, a circuit controller having conducting sections movable relatively to said contacts and terminals and in engagement therewith, said conducting sections of said circuit closer comprising a relatively short section capable of bridging the space from one of said terminals to one of said contacts and a relatively long section capable of bridging substantially all of said contacts and terminals and means responsive to the movements of said elevator for moving said controller relatively to said contact points and terminals for lighting and maintaining lighted successive lights corresponding to points reached and passed by said elevator.

35 9. In an elevator signalling apparatus, a plurality of electrically operated signals, spaced rows of separate contacts for said sig-

nals, means for conducting electricity to a point adjacent said contacts, plural sets of spaced terminals for said conducting means, each set of terminals being placed in one of 5 the rows of contacts, a circuit controller having two series of conducting sections, insulated from one another and movable relatively to said contacts and terminals and in engagement therewith, each series of said conducting sections of said circuit closer comprising a relatively short section capable of bridging the space from one of said terminals to one of said contacts and a relatively long section capable of bridging substantially all of said contacts and terminals and means responsive to the movements of said elevator for moving said controller relatively to said contact points and terminals for lighting and maintaining lighted successive lights 10 corresponding to points reached and passed by said elevator.

10. In an elevator signalling apparatus, a plurality of signal lights for indicating the position of said elevator, conductors leading 25 from said lights and terminating in spaced contact points, the spaced contact points of successive lights forming two parallel series, means for conducting electricity to points adjacent said contact points and terminating 30 in conducting terminals forming the ultimate contact points of said series, the contact points of each light being connected in conducting relation, the corresponding terminals at each of the ends of said series being 35 insulated from one another, a circuit controller movable relatively to said contact points and terminals, said controller having two electrically insulated portions, each adapted to be engaged by one of said series 40 of contact points and terminals, each portion of said controller including conducting and insulating sections for causing a plurality of said lights to be energized in succession and to remain in an energized condition 45 for a predetermined portion of the movement of said elevator, and means responsive to the movements of said elevator for moving said controller relatively to said contact points and terminals for lighting and maintaining 50 lighted successive lights corresponding to points reached and passed by said elevator.

11. In combination with a movable elevator, an electrically actuated signalling mechanism 55 therefor, including a series of lights, a controlling member formed with electrically insulated conducting members, plural sets of contact members for each of said lights, said conducting members being each constructed 60 to be moved progressively into and out of engagement with one of said sets of contacts and means for selectively connecting one of said conducting members at a time with a source of electric current supply and means responsive 65 to the movements of said elevator for

producing relative movement of said controlling member with respect to said contacts.

12. In an elevator motion and position indicator, a commutator, mechanism for actuating said commutator operatively connected with the means for moving the car, a series of lamps lighted seriatim by said commutator and maintained in lighted condition on movement of the car in one direction and a reversing switch operatively connected with the actuating mechanism and reversible thereby for automatically extinguishing the whole series of lighted lamps upon reversal of the movement of the actuating mechanism and at the same time connecting the same lamps into a circuit for lighting seriatim in the reversed order when the commutator reverses its movement.

13. A luminous position and direction of movement indicator for elevators comprising in combination a vertically arranged series of lamps, circuit controlling means for lighting said lamps seriatim in one order starting with a lowermost lamp of the series for the up movement, and in reverse order starting with an uppermost lamp for the down movement and maintaining them lighted in each case to produce the visible effect of a lengthening column of light the head of which advances with the movement of the elevator, said column being a depending column suspended with its base in a fixed position corresponding to the end of the up movement of the elevator and depending therefrom with its free end advancing downwardly with the down movement and for the up movement representing a standing column with a fixed base and a top growing upwardly as the elevator rises.

14. A luminous position and motion indicator for elevators comprising a series of lamps and a commutator therefor, means for moving said commutator synchronously with the motion of the elevator and connected to said lamps and controlling and maintaining the lighting of said lamps, said commutator acting on the series of lamps in an order and succession to produce by the same lamps the effect of a line of light having a fixed end and an advancing or projecting end projecting in one direction for one movement of the elevator and a fixed end and advancing end advancing in the opposite direction for the other or opposite movement of the elevator.

15. In a luminous position and motion indicator for elevators, the combination of a series of lamps, a commutator means for moving said commutator synchronously with the elevator for controlling the lighting of said series of lamps in an order which reverses with the reversal of movement, means for maintaining the circuit of the lighted lamps for either direction of movement of the commutator, and means for collectively and automatically extinguishing the lamps lighted on

the reversal of movement of the elevator, said lamps being lighted and maintained to produce a luminous column inverted or upright for the down and up movements of the elevator respectively, the direction in which said column extends from its base corresponding to a limit of motion of the elevator indicating for both the up and down movement the direction in which the elevator is moving.

16. Electrical signalling mechanism for indicating the direction of movement and position of an elevator comprising a series of lamps and a synchronously moving commutator means for moving said commutator synchronously with the elevator and having an elongated conducting section for lighting the series of lamps seriatim in one order upon movement in one direction and maintaining them lighted and another conducting section for lighting the lamps in the reverse order upon movement in the opposite direction and a transfer switch for automatically completing the connections through the lamps and one or the other of said sections automatically by reversal of movement of the elevator.

17. A motion and position indicator for elevators comprising in combination a series of electric lamps, a commutator, and means for moving said commutator synchronously with the elevator, said commutator controlling the lighting of said lamps and maintaining the lighting of them in series beginning with a lamp thereof corresponding to the position from which the elevator starts its movement to produce a luminous column whose advancing end corresponding to the last lighted lamp of the series represents the motion of the elevator while the position of said advancing end indicates the position of the elevator, the length of the column representing the extent to which the elevator has moved from said starting position.

18. In an elevator signal system, in combination with an elevator, means to indicate the progress and direction of travel of the elevator comprising a signal panel at a floor, a group of index elements equal in number to the number of floors and arranged in single file formation on said panel, a circuit to each of said index elements, means for closing (and holding closed) each of said circuits in succession as the elevator arrives adjacent the respective floors, and means operable upon the reversal of the elevator's direction of travel at any location in its path of travel to open all of said circuits and at the same time close all the circuits previously open, said means further operating to maintain a closed circuit to the index element representing the floor at which the reversal of the elevator occurs; the opening and closing of all said circuits occurring simultaneously.

19. In an elevator signal system, in combination with an elevator, means to indicate the progress and direction of travel of the

elevator comprising a signal panel at a floor, a group of index elements equal in number to the number of floors and arranged in single file formation on said panel, a circuit to each of said index elements, means for closing (and holding closed) each of said circuits in succession as the elevator arrives adjacent the respective floors, and means operable upon the reversal of the elevator's direction of travel at any location in its path of travel to open all of said circuits and at the same time close all the circuits representing the floors not reached by the elevator at the time of its reversal said means further operating to maintain a closed circuit to the index element representing the floor at which the reversal of the elevator occurs.

20. In an elevator signal system, in combination with an elevator, means to indicate the progress and direction of travel of the elevator comprising a signal panel at a floor, a group of index elements equal in number to the number of floors and arranged in single file formation on said panel, a circuit to each of said index elements, means for closing (and holding closed) each of said circuits in succession as the elevator arrives adjacent the respective floors, means for re-opening all said circuits except the one last closed, said means operating upon the reversal of the elevator's direction of travel at any location in its path of travel, and means for reclosing (and holding closed) each of said circuits in the reverse succession as the elevator retraces the same portion of its path of travel.

21. In an elevator signal system, an elevator, means to indicate the position of said elevator comprising a signal panel at a floor, a group of index elements equal in number to the number of floors, and arranged in file formation on said panel, means for indicating on said panel the direction of travel and also the progress of said elevators, said means comprising electrical means for causing the progressive energization of the same index elements in synchronism with both the upward and downward movements of said elevator from floor to floor, said electrical means including circuits to said index elements and a commutator current maintaining switch movable in synchronism with the associated elevator, means for rendering said commutator switch ineffective with respect to the maintenance of said circuits, and means for maintaining a current in the circuit to either extreme index element irrespective of the operation of said last-named means.

22. In an elevator signal system, an elevator, means to indicate the position of said elevator comprising a signal panel at a floor, a group of index elements equal in number to the number of floors, and arranged in file formation on said panel, and means for indicating on said panel the direction of travel and also the progress of said elevator, said

means comprising electrical means for causing the progressive energization of the same index elements in synchronism with both the upward and downward movements of said elevator from floor to floor, said electrical means including circuits to said index elements and a commutator switch movable in synchronism with the motion of the associated elevator, said commutator switch 10 comprising an elongated carriage having an electrical contact surface and a plurality of contact segments equal in number to the number of floors, said contact segments being disposed adjacent said carriage.

23. In an elevator signal system, an elevator, means to indicate the position of said elevator comprising a signal panel at a floor, a group of index elements equal in number to the number of floors, and arranged in file 20 formation on said panel, means for indicating on said panel the direction of travel and also the progress of said elevator, said means comprising electrical means for causing the progressive energization of the same index 25 elements in synchronism with both the upward and downward movements of said elevator from floor to floor, said electrical means including circuits to said index elements and a commutator current maintaining switch for 30 said circuits, said commutator switch comprising an elongated carriage having an electrical contact surface and a plurality of contact segments equal in number to the number of floors, said contact segments being disposed adjacent said carriage, and means for 35 connecting said carriage with said elevator for proportionate movement therewith.

24. In an elevator signal system, an elevator, means to indicate the position of said elevator comprising a signal panel at a floor, a group of index elements equal in number to the number of floors, and arranged in file 40 formation on said panel, means for indicating on said panel the direction of travel and also the progress of said elevator, said means comprising electrical means for causing the progressive energization of the same index 45 elements in synchronism with both the upward and downward movements of said elevator from floor to floor, said electrical means including circuits to said index elements and a commutator current maintaining switch movable in synchronism with the motion of the associated elevator, said commutator 50 switch comprising an elongated carriage having an electrical contact surface and a plurality of contact segments equal in number to the number of floors, said contact segments being disposed adjacent said carriage, and means for 55 rendering said carriage ineffective with respect to the maintenance of all of said circuits with the exception of the circuit to either extreme index element.

25. In an elevator signalling apparatus, 60 the combination with an elevator car, of an

indicator panel having a plurality of light transmitting areas representing, in order, different locations in the elevator hatchway to which said elevator car may move, each of said areas being displayed when illuminated 70 from the rear of said panel, and mechanism actuated in accordance with the position and direction of travel of said elevator car for controlling the illumination of said areas from the rear of said panel to build up, by 75 the same series of light transmitting areas, a gradually lengthening display of successive areas indicating the position and either direction of movement of the elevator car, said display of successive areas for the upward travel of the elevator car having a fixed base maintained in the position corresponding to the down position of the elevator car and lengthening toward the position corresponding to the up position of the elevator car 85 in accordance with upward car travel, and, for the downward travel of the elevator car, having a fixed base maintained in the position corresponding to the up position of the elevator car and lengthening toward the position corresponding to the down position of the elevator car in accordance with downward car travel.

26. In combination with an elevator car vertically movable between a lower and an upper terminal, a signalling mechanism comprising a plurality of electrically energized elements, means controlled by the position of said elevator car for successively energizing said elements, said means causing certain 95 of the energized elements to remain in an energized state after succeeding elements have been energized, and means, effective in the event said elevator car, during a trip from either terminal, reverses before it arrives at the other terminal, for breaking the energizing circuit of said energized elements and for completing an energizing circuit for such elements as would correspond with the movement of said elevator car in the direction from the terminal not reached to the floor at which such reversal takes place.

27. In combination with an elevator car, means to indicate the progress and direction of travel of the elevator car, comprising, a signal panel at a floor, a group of index elements equal in number to the number of floors and arranged in single file formation on said panel, a circuit to each of said index 115 elements, means for closing (and holding closed) each of said circuits in succession as the elevator car arrives at a position in the elevator shaft corresponding thereto, and means operable upon a reversal in the direction of travel of the elevator car at any location in its path of travel to open the energizing circuit of said energized elements and at the same time to complete an energizing circuit for such elements as would indicate 120 movement of the elevator car in the opposite 125 direction. 130

direction from the terminal floor to the floor at which such reversal takes place.

28. In combination with a vertically movable elevator car operable between two terminal positions; an indicating panel having arranged in single file formation thereon a plurality of small, substantially uniform areas representative of different points, including said terminal positions, in the travel of said elevator car, each of said areas being displayed by illumination passing therethrough from the rear thereof; and means actuated in accordance with the position and direction of travel of said elevator car for causing, when said elevator car is at either of said terminal positions, the display of only the area representative of the terminal position at which said elevator car is located, and for causing, when said elevator car is between said terminal positions and progressing from either terminal position toward the other, the continuous display of the area representative of the terminal position from which said elevator car is progressing and also the continuous display of successive areas extending from such displayed terminal area to an area indicative of the position of said elevator car.
29. In an elevator signalling apparatus, the combination with an elevator car operable between two terminal positions; of an indicator panel having a plurality of light transmitting areas representing, in order, different locations in the elevator hatchway, including said terminal positions, to which said elevator car may move, each of said areas being displayed when illuminated from the rear of said panel; and mechanism actuated in accordance with the movement of said elevator car for causing the illumination of only the area representative of the lower terminal when said elevator car is at the lower terminal position, and for causing, when said elevator car is away from said lower terminal and is progressing in the direction of the upper terminal, the continuous illumination of the area representative of the lower terminal and also the continuous illumination of the other areas, exclusive of the area representative of the upper terminal, successively in accordance with the movement of said elevator car in the hatchway past the locations corresponding thereto, and for causing, when said elevator car arrives at the upper terminal, the illumination of the area representative of the upper terminal and the extinguishment of the illumination for all other areas.
30. A position and direction-of-travel indicator for an elevator car, comprising; a signal panel; a terminal signal light for the lower terminal floor served by the elevator car mounted on said signal panel; a terminal signal light for the upper terminal floor served by the elevator car mounted on said panel at

a space from said first named terminal signal light; a plurality of intermediate signal lights, representative of different points in the travel of said elevator car between said two terminal floors, mounted on said signal panel in single file formation in said space between said two terminal signal lights; and switching mechanism actuated in accordance with the movement of said elevator car for causing the energization of only the terminal signal light for the lower terminal floor when said elevator car is at the lower terminal floor and the energization of only the terminal signal light for the upper terminal floor when said elevator car is at the upper terminal floor, and for causing, when said elevator car is between said terminal floors on a trip in a direction from either terminal floor, the continuous energization of the terminal signal light for the terminal floor from the direction of which such trip is progressing and also the continuous energization of certain of said intermediate signal lights in accordance with car travel so as to form a continuous succession of energized signal lights of which the end removed from the energized terminal signal light is indicative of the position of said elevator car, whereby the position of the elevator car is always indicated whether the elevator car is between terminal floors or is at either terminal floor, and the direction of travel of the elevator car when it is between terminal floors is represented by the direction in which the continuous succession of energized signal lights extends from the energized terminal signal light.

Signed at New York, in the county of New York and State of New York this 1st day of April A. D. 1926.
